189,247

BEAUTY SHOP BOOTH UNIT OR SIMILAR ARTICLE

Fred J. Piotraschke, 8032 Carondelet Ave., Clayton, Mo.

Filed Nov. 23, 1959, Sér. No. 58,423

Term of patent 7 years

(Cl. D33—19)

FIG. 1.

FIG. 2

Figure 1 is a front perspective view of a beauty shop booth unit or similar article; and

Figure 2 is a front elevational view thereof.

The rear and the side not shown are substantially plain.

I claim:

The ornamental design for a beauty shop booth unit or similar article, as shown and described.

References Cited in the file of this patent

UNITED STATES PATENTS

D. 80,661	Paik	Mar. 4, 1930
D. 96,785	Stentiford	Sept. 3, 1935
D. 141,128	Stanitz	May 8, 1945
D. 183,996	McCartan	Nov. 25, 1958
D. 185,096	Piotraschke	May 5, 1959

OTHER REFERENCES

New Dimensions by Kochs Company, Catalog No. 78, received October 30, 1958, page 25, items No. 6003 and No. 5401.